CLAIM

The ornamental design for a clip for a bottle and a syringe, as shown and described.

DESCRIPTION

FIG. 1 is a perspective view of the front, top and side of the inventive clip for a bottle and a syringe;

FIG. 2 is a top plan view of the clip for a bottle and a syringe;

FIG. 3 is a side elevation of one side of the clip for a bottle and a syringe, the opposite side being symmetrically identical;

FIG. 4 is a rear elevation thereof; and,

FIG. 5 is a front elevation thereof.

The broken lines showing a bottle and a syringe in FIG. 1 are for illustrative purposes only and do not form part of the claimed design.
